US0D1045077S

(12) **United States Design Patent** (10) **Patent No.:** **US D1,045,077 S**
(45) **Date of Patent:** **** Oct. 1, 2024**

(54) **STETHOSCOPE DIAPHRAGM**

(71) Applicant: **CHIN KOU MEDICAL INSTRUMENT CO., LTD.**, New Taipei (TW)

(72) Inventor: **Chung-Jen Wong**, New Taipei (TW)

(73) Assignee: **CHIN KOU MEDICAL INSTRUMENT CO., LTD.**, New Taipei (TW)

(**) Term: **15 Years**

(21) Appl. No.: **29/760,307**

(22) Filed: **Nov. 30, 2020**

(51) **LOC (14) Cl.** **24-02**

(52) **U.S. Cl.**

USPC **D24/134**

(57) **CLAIM**

The ornamental design for a stethoscope diaphragm, as shown and described.

DESCRIPTION

FIG. 1 is a perspective view of a stethoscope diaphragm showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The dash-dash broken lines depict portions of the stethoscope diaphragm that form no part of the claimed design.

1 Claim, 7 Drawing Sheets
